CLAIM

The ornamental design for a beach chair exerciser, as shown and described.

DESCRIPTION

FIG. 1 is a front-right-top perspective view of a beach chair exerciser, showing my new design;

FIG. 2 is a front elevational view thereof, the opposite side being a mirror image;

FIG. 3 is a left elevational view thereof;

FIG. 4 is a right elevational view thereof;

FIG. 5 is a top plan view thereof; and,

FIG. 6 is a bottom plan view thereof.

FIG.1

FIG. 2

FIG. 3

FIG. 4

FIG. 5

FIG. 6
